UNITED STATES PATENT OFFICE.

RACHEL SUDIAH, OF NEW YORK, N. Y.

DETACHABLE BUTTON.

1,219,188.

Specification of Letters Patent. Patented Mar. 13, 1917.

Application filed May 17, 1915. Serial No. 28,508.

To all whom it may concern:

Be it known that I, RACHEL SUDIAH, a citizen of the United States, residing in the city of New York, borough of Bronx, county 5 of Bronx, and State of New York, have invented a certain new and useful Detachable Button, of which the following is a specification.

This invention is a detachable button, and 10 the object of the invention is to provide means for detachably securing a button to a fabric by metallic means, in a simple and convenient manner and without the necessity of tools.

15 It has heretofore been suggested to secure buttons to a fabric by metallic means, but, in every case, the structure was such as to be extremely complicated, or, if of a simple nature, necessitated the use of tools of particular construction for securing the button to the fabric. Moreover, in the majority of cases, the buttons, when in place, were held 20 in such manner that they could not be removed and were, therefore, of absolutely no 25 utility where removable buttons were required.

With the foregoing disadvantages in mind, the present invention embodies means whereby the button may be detachably secured to 30 a fabric in a simple and convenient manner, and the construction is such as to adapt it for use on the most light and fragile fabrics, without, in any way, tearing or disrupting the fabric.

35 The invention embodies a piece of wire adapted to engage, intermediate its ends, with the eye or loop of a button, the free ends of said wire being adapted to be passed through a fabric and through the aperture 40 of an attaching plate positioned at the back of said fabric, whereupon said wire is adapted to be bent to form two diverging arms which may be detachably locked by engaging means embodied in the attaching plate.

45 Features of the invention, other than those specified, will be apparent from the hereinafter detailed description taken in conjunction with the accompanying drawings.

In the accompanying drawings, I have 50 illustrated one practical embodiment of the invention, but the construction shown therein is to be understood as illustrative, only, and not as defining the limits of the present invention.

55 Figure 1 is a side elevation of button attaching means embodying the present in-

vention, certain parts being shown in section in the interest of clearness.

Fig. 2 is a face view on the wrong side of the fabric, showing the manner in which 60 the wire which holds the button in place is detachably secured to the attaching plate.

Fig. 3 is a cross-section through the attaching member, on line 3—3 of Fig. 2, and

Fig. 4 shows a piece of wire bent to the 65 form for readily attaching the button.

Referring to the drawings, A indicates a piece of fabric, to which it is adapted to secure a button. B denotes a button of any well known, conventional form, which it is 70 desired to secure to the fabric. The button which has been shown for illustrative purposes is provided with an eye c, through which stitches are generally passed when the well known method of sewing on buttons is 75 practised. According to the present invention, however, a piece of wire C is employed. The wire C is preferably bent upon itself so as to form a loop centrally of its extent, whereby the wire assumes the general appearance of the well known cotter-pin (see Fig. 4), and, for this reason, it will be hereinafter referred to as such, for the sake of brevity.

In attaching button B to the fabric, one 85 leg of pin C is passed through loop c of the button so that the eye of said pin engages with the loop. The free ends of the pin are then thrust through the fabric and through a central aperture d in an attaching plate D 90 positioned on the wrong side of the fabric. Plate D is preferably stamped from sheet metal and is provided with a pair of oppositely positioned, coöperating tongues d' 95 d'', which are in parallel relation and face in opposite directions. Moreover, these tongues are stamped up from plate D so as to lie in a plane parallel to the face of the plate, in spaced relation to said plate.

After pin C has been passed through aperture d of plate D, the free ends of said pin are adapted to be bent over into diverging alinement, as shown in dotted lines in Fig. 2, whereupon rotation of the plate or pin will cause the free ends of pin C to pass 100 under tongues d' d''. In order to hold the free ends of the pin in this position, depressions e e' are preferably formed in the plate D, so as to extend radially beneath the tongues d' d''. Being of metal, plate D and, 110 consequently, tongues d' d'' are more or less resilient, and, this being the case, the free

ends of the pin, when forced beneath the tongues, seat in the depressions $e e'$, thereby locking the parts against relative movement and securing the pin against withdrawal, as 5 shown in Fig. 3.

When it is desired to detach the button the foregoing operation is reversed, *i. e.*, the parts are given relative movement to force the pin C out of the depressions $e e'$ beneath 10 the tongues $d' d^2$ and into the position shown in dotted lines in Fig. 2. The pin is then unbent or straightened out into the form shown in Fig. 4, whereupon it may be readily withdrawn from attaching plate D 15 and fabric A. The wire from which pin C is formed is of a malleable nature, so that it may be readily bent in the manner specified, without the necessity of tools and, moreover, may be manipulated many times without 20 fear of breakage.

It will be manifest, from the foregoing, that the attachment of the present invention is extremely simple and may be attached or detached in an expeditious manner 25 and without the necessity of any skill whatsoever. The structure is such that the attachment places no strain whatever upon the fabric to which it is attached and only a very small perforation in the fabric is required in attaching the button. The present 30 invention is therefore, particularly adapted for use on shirtwaists where such light materials as lace, chiffon, crêpe de chine, or other light and fragile material, are generally employed. Furthermore, I have found the button to be very efficient when used on wash-vests, the structure being such as to allow of the removal of the buttons for the 35 purpose of washing.

When used on such light dressgoods as hereinbefore mentioned, the attaching member may, if desired, be formed from celluloid or other material than metal, and may be colored to harmonize with the goods with 40 which it is adapted to be associated. It, therefore, passes unobserved, even though the button is turned back in such manner as to otherwise expose said attaching member to view.

It has been heretofore suggested to fasten 45 a button to material, such as leather, by forcing a staple through the leather and then turning back the ends into intimate contact with the leather in such manner that it will sink thereinto and hold the button in place. Manifestly, structures of this character are 50 absolutely prohibitive in the attachment of buttons to such light fabrics as hereinbefore specified, as they could never be detached

without tearing the material, and, moreover, 60 the mode of attachment is such that it would not hold in such fragile goods.

It will be noted, particularly from Fig. 3, that the free ends of the tongues d' and d^2 are turned in toward the attaching plate. 65 This is the preferred embodiment of the invention, the inturned portions of the tongues being adapted to absolutely preclude their disengagement with the pin even though the pin becomes disengaged from the depressions 70 $e e'$. The natural resiliency of the tongues, however, allow of the ready positioning or disengagement of the pin with its respective tongues when it is desired to attach or detach the button, but, manifestly, the pin cannot inadvertently work loose. The invention is, however, not limited to the aforesaid turned-in tongues, as they are employed only 75 as an additional precaution, and are not absolutely essential. The tongues may, if desired, be made straight, and may, moreover, be of malleable nature so that they may be slightly bent down after the pin is in place. This may be accomplished absolutely without tools, as the attaching plate is constructed 80 of light material, and may be readily manipulated.

Having thus fully described the invention, what I claim as new, and desire to secure by Letters Patent, is:—

As a new article of manufacture, detachable button-securing means embodying an attaching plate provided with a centrally disposed aperture, and a pair of coöperating tongues integral with said plate and positioned adjacent said aperture so as to face, in opposite directions, said plate being provided with a pair of depressed channels radiating from said aperture in diverging relation and extending into juxtaposition 100 with the tongues, in combination with a malleable pin adapted to be secured to a button and having a pair of legs adapted to be passed through the aperture in the plate and thereafter bent over into diverging relation 105 and rotated to seat the bent-over portions of said legs in the depressed channels of the plate and beneath the tongues, whereby the tongues operate to maintain said bent-over portions against inadvertent displacement 110 from said channels for the purpose of detachably locking the button in position, said legs being of such length as not to extend beyond the periphery of the plate.

In testimony whereof I have signed my 115 name to this specification.

RACHEL SUDIAH.
